CLAIM

The ornamental design for a data module for modular wiring system, as shown and described.

DESCRIPTION

FIG. 1 is a perspective view of a data module for a modular wiring system showing our new design;

FIG. 2 is a side elevational view thereof, the opposite side is identical;

FIG. 3 is an end elevational view thereof, the opposite end is identical;

FIG. 4 is a top plan view thereof; and,

FIG. 5 is a bottom plan view thereof.
